US0D1032110S

(12) **United States Design Patent** (10) **Patent No.:** **US D1,032,110 S**
(45) **Date of Patent:** **** Jun. 18, 2024**

(54) **COORDINATION TRAINING APPARATUS**

(71) Applicant: **Dongguan Jierui Sports Goods Co., Ltd.**, Dongguan (CN)

(72) Inventor: **Zuosi Rao**, Dongguan (CN)

(73) Assignee: **Dongguan Jierui Sports Goods Co., Ltd.**, Dongguan (CN)

(**) Term: **15 Years**

(21) Appl. No.: **29/833,913**

(22) Filed: **Apr. 7, 2022**

(51) **LOC (14) Cl.** **21-01**

(52) **U.S. Cl.**

USPC **D21/468**; D21/441; D21/437; D21/436

(58) **Field of Classification Search**

USPC D21/437, 441, 443, 468, 682, 684, 694, D21/791, 830; D30/160

CPC A63B 21/4035; A63B 24/0021; A63B 2022/0092; A63B 21/4019

See application file for complete search history.

(57) **CLAIM**

The ornamental design for a coordination training apparatus, as shown and described.

DESCRIPTION

FIG. 1 is a perspective view of a coordination training apparatus, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.
